RAZOR BLADE STROPPER

Edward D. Perry, Waterbury, Conn., assignor to
The Beardsley & Wolcott Manufacturing Com-
pany, Waterbury, Conn., a corporation of Con-
necticut

Application August 3, 1931, Serial No. 554,639

12 Claims. (Cl. 51—80)

This invention relates to stroppers, and more particularly to a hand-operated device for simultaneously stropping both sides of both edges of a double-edged safety razor blade.

5 One object of this invention is to provide a handle-operated blade stropper of the above nature, constructed in substantially cylindrical shape for facilitating the holding of the device in the left hand of the operator, while he rotates the handle with his right hand.

10 A further object is to provide a device of the above nature provided with a casing, the end walls of which have cam edges and vertical slots for guiding the upper stropper rolls into stropping position and limiting the inward movement thereof, to prevent them from being cut by a razor blade.

15 A further object is to provide a stropper of the above nature having a much smaller number of gears for driving the stropper roll than were formerly required in stropping devices of this kind.

20 A further object is to provide a device of the above nature which will be simple in construction, inexpensive to manufacture, which shall consist of relatively few parts and which will be compact, ornamental in appearance, and highly efficient and durable in use.

25 With these and other objects in view there has been illustrated on the accompanying drawing one form in which the invention may be conveniently embodied in practice.

30 In the drawing:

Fig. 1 represents a perspective end view of the improved stropper embodying the invention.

35 Fig. 2 is a longitudinal sectional view of the same.

Fig. 3 is a front view of the same, partly broken away, to show the interior construction.

40 Fig. 4 is a transverse sectional view taken on the line 4—4 of Fig. 2, looking in the direction of the arrows, and showing the arrangement of the operating gears.

45 Fig. 5 is a transverse sectional view taken on the line 5—5 of Fig. 2, looking in the direction of the arrows, and showing the covers in open position, with a razor blade resting upon the lower stropping rolls.

50 Fig. 6 is a rear end view of the stropper, on a slightly enlarged scale, showing in full lines, the cover sections in depressed position, the dot and dash lines indicating the normal raised position thereof.

55 Fig. 7 is a front view of the operating gears in their normal condition.

Fig. 8 is a similar front view of said gears in their depressed position.

Referring now to the drawing in which like reference numerals denote corresponding parts throughout the several views, the numeral 10 indicates a hollow base which is substantially semi-cylindrical in shape, and has a pair of vertical end walls 11. The end walls 11 are provided with depending large central slots 12 in their top edges, and said top edges also have 10 slots 13 and 13a, which serve to limit the inward swinging of a pair of upper stropper roll shafts 14 and 15, said shafts 14 and 15 being journaled in a pair of end plates 16 and 17 forming part of a pair of quarter-cylindrical hollow cover 15 members 18 and 19, respectively, said cover members being loosely joined to said base frame 10, as by a pin and slot connection to be described later.

The upper edges of the end walls 11 are also 20 provided with inclined cam sections 20 and 21, for guiding the movable shafts 14 and 15 into the slots 13 and 13a, when the covers 18 and 19 are being closed. The blade 21a will thus be prevented from cutting the stropping elements 25 which preferably consist of two pairs of narrow leather strips 22 and 22a, helically wound on the exterior of the two sets of cooperating stropper rollers 23 and 24, 25 and 26, carried by the shafts 14, 15, 27, 28, respectively. 30

The helical strips 22 on the upper rolls 23 and 24 are arranged in staggered relationship with respect to the similar leather strips 22a, formed on the lower rolls 25, 26, so as to prevent 35 said strips from contacting with each other during the rotation of said rolls.

The cover members 18 and 19 are provided with small vertical slots 29 and 30 on their opposite end plates 16 and 17 thereof for loosely receiving the extremities of the stationary shafts 27 and 28 which are journaled in the end walls 11 of said base frame 10. By means of this construction, it will be seen that the cover members 18 and 19 carrying the movable upper stropper rolls 23 and 24 will be loosely and adjustably pivoted with respect to the lower stationary rolls 25 and 26. 40

In order to provide manually-operated means for rotating all four of the stropper rolls 23, 24, 25 and 26 simultaneously against the opposite 50 sides of the two edges of the razor blade 21a, provision is made of a handle arm 31 provided at its outer end with an operating knob 32, said handle 31 being provided at its inner end with a spiral-shaped key slot 33 loosely fitted about 55

a pin 34 projecting from the extremity of the lower stationary shaft 28. The connection between the pin 34 and the key slot 33 is such that the rotation of the handle arm 31 in the direction of the arrow shown in Fig. 3 will cause the rollers 23, 24, 25, and 26 to stop the blade 21a. If, however, the handle 31 should be rotated in the opposite direction it will slip with respect to the extension pin 34 and injury to the helical stropper strips 22 and 22a by the razor blade 21a will thus be prevented.

The power imparted to the driving shaft handle 31 is communicated to the other stropper shafts 14, 15 and 27 by means of three sets of intermeshing gears arranged as follows:—gears 35 and 36 mounted on the upper movable shafts 14 and 15, gears 37 and 38 mounted on the lower stationary stropper shafts 27 and 28, and a pair of idle pinions 39 and 40 mounted to rotate on a pair of pins 41 and 42 carried by the front end wall 11 of the base frame 10.

In order to permit the pressure of the four stropper rolls upon the razor blade 21a to be varied at will during the stropping operation, provision is made of a pair of centrally located vertical plungers 43 and 44 having flanges 45 at their lower ends, and adapted to be slidably fitted within a pair of tapped housings 46 and 46a. The housings 46 and 46a are secured to the bottom wall of the base frame 10 by means of a pair of screw plugs 47 and 47a.

The upper adjacent edges of the covers 18 and 19 are provided with corrugated outer surfaces 48 and 49, adapted to be engaged by the fingers of the operator for depressing said covers with respect to said base frame 10 against the tension of a pair of coiled springs 50 and 51 located within the plunger housings 46 and 46a and pressing upwardly at all times upon the vertical plungers 43 and 44. The plungers 43 and 44 are adapted to be spaced apart the proper distance for receiving the usual end apertures of the razor blade 21a.

45 Operation

In operation, the razor blade 21a will first be dropped over the plungers 43 and 44 into the position shown in Fig. 5. The cover members 18 and 19 will then be closed, bringing their adjacent edges into contact with the upper ends of said plungers, and the user will grasp the device in his left hand while rotating the crank handle 31 with his right hand. The pressure of the stropper rolls 23, 24, 25 and 26 upon the razor blade 21a may be readily adjusted by varying the pressure with which the upper covers 18 and 19 are squeezed downwardly toward the base frame 10.

60 One advantage of the present invention lies in the fact that the cylindrical shape of the stropper enables it to conform comfortably to the hand of the user and permits greater accuracy of control of the device than was the case with prior devices.

65 While there has been disclosed in this specification one form in which the invention may be conveniently embodied, it will be understood that the invention is not to be limited thereto, but may be modified and embodied in various other forms without departing from its spirit. In short, the invention includes all the modifications and embodiments coming within the scope of the following claims.

75 Having thus fully described the invention,

what is claimed as new and for which it is desired to secure Letters Patent is:

1. In a stropper for a double edged razor blade, a stationary base, a pair of lower stropper rolls journaled in said base, a pair of cover members loosely pivoted to said base and carrying a pair of movable stropper rolls, means for holding a razor blade in stropping position in contact with all four of said rolls, resilient means at the center of said blade for pressing said cover members upwardly, said base and cover members having a substantially cylindrical shape to conform comfortably to the user's hand, said base having a pair of upstanding end plates, each of said end plates having a vertical slot for receiving one of said upper stropper rolls for limiting its inward movement and thus preventing cutting of said roll by the razor blade. 5

5 journaled therein, a pair of carrier members pivotally connected to said stationary base and carrying a pair of movable stropper rolls therein, means for holding said razor blade in stropping position in contact with all four rolls, and cam 10 means for holding said upper rolls upwardly out of stropping position while said carrier members are being swung into operating position, whereby cutting of said upper stropper 15 rolls by said blade will be prevented.

6. In a device for stropping both sides of a 15 double edged razor blade at the same time, a stationary base having a pair of lower stropper rolls journaled therein, a pair of carrier members pivotally connected to said stationary base and carrying a pair of movable stropper rolls therein, means for holding said razor blade in stropping position in contact with all four rolls, and means for holding said upper rolls upwardly 20 out of stropping position while said carrier members are being swung into operating position, whereby cutting of said upper stropper rolls by said blade will be prevented.

7. In a device for stropping both sides of a 25 double edged razor blade at the same time, a stationary base having a pair of lower stropper rolls journaled therein, a pair of carrier members pivotally connected to said stationary base on the axis of said lower stropper rolls and carrying a pair of movable stropper rolls therein, means for holding said razor blade in stropping position in contact with all four rolls, and cam 30 means for holding said upper rolls upwardly out of stropping position while said carrier members are being swung into operating position, whereby cutting of said upper stropper rolls by said blade will be prevented.

8. In a device for stropping both sides of a 35 double edged razor blade at the same time, a stationary base having a pair of lower stropper rolls journaled therein, a pair of carrier members pivotally connected to said stationary base on the axes of said lower stropper rolls and carrying a pair of movable stropper rolls therein, means for holding said razor blade in stropping position in contact with all four rolls, each carrier member being connected to both ends of one of said lower stropper rolls, and mechanism 40 including gears mounted on said upper rolls in direct mesh with gears mounted on said lower rolls arranged to rotate said upper and lower rolls simultaneously in opposite directions.

9. In a stropper for a double edged razor 45 blade, a stationary base, a pair of lower stropper rolls journaled in said base, a pair of cover members having a pin and slot connection with said base and each pivoted at both ends on the axes of said lower rolls and carrying a pair of movable stropper rolls, means for holding a 50 razor blade in stropping position in contact with all four of said rolls, spring means at the center of said blade for pressing said cover members upwardly, said base and cover members having 55

a substantially cylindrical shape to conform comfortably to the user's hand, and manually operated gears mounted on said upper rolls in direct mesh with gears mounted on said lower rolls and arranged to rotate said rolls simultaneously in opposite directions. 5

10. In a stropper for a double edged razor 10 blade, a stationary base, a pair of lower stropper rolls journaled in said base, a pair of cover members having a pin and slot connection with said base and each pivoted at both ends on the axes of said lower rolls and carrying a pair of movable stropper rolls, means for holding a razor 15 blade in stropping position in contact with all four of said rolls, a pair of spring-pressed blade-guiding plungers for guiding said blade and for pressing said cover members upwardly, said base and cover members having a substantially cylindrical shape to conform comfortably to the user's hand, each of said rolls carrying a gear 20 on one end, the gear on each upper roll meshing with the gear on the cooperating lower roll, and a pair of idler gears for interconnecting the gears on said lower rolls.

11. In a stropper for a double edged razor 25 blade, a stationary base, a pair of lower stropper rolls journaled in said base, a pair of cover members having a pin and slot connection with said base and each pivoted at both ends on the axes of said lower rolls and carrying a pair of movable stropper rolls, means for holding a razor 30 blade in stropping position in contact with all four of said rolls, spring means at the center of said blade for pressing said cover members upwardly, said base and cover members having a 35 substantially cylindrical shape to conform comfortably to the user's hand, said cover members having corrugated adjacent upper surfaces to prevent slippage, and gear mechanism including 40 gears mounted on said upper rolls in direct mesh with gears mounted on said lower rolls to cause said upper rolls to operate simultaneously in the opposite direction from said lower rolls.

12. In a stropper for a double edged razor 45 blade, a stationary base, a pair of lower stropper rolls journaled in said base, a pair of cover members having a pin and slot connection with said base and each pivoted at both ends on the axes of said lower rolls and carrying a pair of movable stropper rolls, means for holding a 50 razor blade in stropping position in contact with all four of said rolls, spring means at the center of said blade for pressing said cover members upwardly, said base and cover members having a substantially cylindrical shape to conform 55 comfortably to the user's hand, said covers having slots to slidably fit over pins extending from said lower stropper rolls, and manually operated gears mounted on said upper rolls in direct mesh with gears mounted on said lower 60 rolls and arranged to rotate said rolls simultaneously in opposite directions.

EDWARD D. PERRY.
